UNITED STATES PATENT OFFICE.

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS.

KNITTED STOCKING.

Application filed September 1, 1922. Serial No. 585,708.

To all whom it may concern:

Be it known that I, WILLIAM S. PARKER, a citizen of the United States, residing at Rockford, in the county of Winnebago and 5 State of Illinois, have invented certain new and useful Improvements in Knitted Stockings, of which the following is a specification.

This invention pertains in general to 10 knitted fabrics, and while the principles thereof may be embodied in fabrics for various purposes, I have chosen for the specific illustration of the invention in this application, a knitted stocking in which the 15 invention is incorporated.

The primary purpose of the invention is to provide a fabric having a cord yarn or strand of any character of substantial cross-sectional area secured to one face thereof so 20 as to lend additional strength to the fabric in the direction of the wales and to give the appearance from the opposite face of the fabric of a rib, or when located at the back of a seamless fashioned or a seamless tubular stocking, the appearance of a mock 25 seam.

This reenforcing strand or member, which will hereafter be referred to as a cord, the word cord being used in a generic sense 30 to include any suitable flexible element whether twisted, braided or otherwise formed, is secured to the body of the fabric by spaced floating yarns, resulting from certain types of stitches formed at predetermined points in the body of the fabric during 35 the knitting operation.

One embodiment of the invention is illustrated on the accompanying drawings from which it will be apparent that—

40 Fig. 1 is a back view of a knitted stocking embodying my invention;

Fig. 2 is an enlarged fragmentary face view of the fabric; and

45 Fig. 3 is a sectional view on the line 3—3 of Fig. 2.

The fabric illustrated comprises wales, those of which are illustrated in the fragment of the fabric shown in Fig. 2 being indicated by reference characters 5 to 15, 50 inclusive.

This fabric is of plain knitting with the exception that in certain wales an open work effect is produced by stitches of a special type or character including floating yarns on the inner side of the fabric adapted for

holding and presenting to view at the face of the fabric a mock seam cord, as will be presently described. This open work effect may be produced in various ways, such, for example, as either by draw or tuck stitches; 60 and in the fabric shown in Fig. 2 draw stitches are used. The courses of this fabric are designated by reference characters 16 to 26 inclusive. These courses are of plain knitting except that in every third course, 65 i. e., in courses 18, 21 and 24 the loops are held during two successive courses by the needles knitting the wales 9, 10 and 11, to produce draw stitch loops 28 which leave the floating yarns 27 at the back or inner 70 side of the fabric. The floating yarns and draw stitch loops may be of any desired length, although it is essential that they or the equivalent shall be in alignment, preferably as shown, in order to secure the desired location of the mock seam. The remainder of the fabric may be of any character desired.

The cord which has heretofore been mentioned and which is designated on the drawings by reference character 29, is attached to the back of the fabric by the floating yarns 27 between which and the web of the fabric the cord is introduced subsequently to the completion of the knitting, the cord 80 being threaded or drawn beneath the floating yarns by hand or in any other preferred manner. This cord may be of the same color as the fabric or of any other desired color, and since it lies back of the elongated 85 draw stitches, it can be seen from the front of the fabric through the eyelets or apertures resulting from the draw stitch structure.

When the fabric is taut, as for instance, 90 when a stocking is being worn, it presents along the line of the cord, the appearance of a rib and, if disposed at the back of a seamless fashioned stocking indicated generally by reference character 30 in Fig. 1, 100 the corded structure resembles a mock seam, which is indicated by reference character 31. The corded structure not only enhances the appearance of the fabric, but also reenforces and strengthens the same, which is particularly desirable at the back of a stocking where it frequently gives way under the excessive strains resulting from pulling the stocking on over the heel of the wearer.

It should be apparent from the foregoing 110

that I have provided a fabric adapted for a wide variety of purposes, which possesses not only the advantage of a novel and attractive appearance, but also the desirable 5 feature of reinforcement to the fabric structure which materially increases its longevity. Various adaptations of the principle of this invention may obviously be resorted to without departing from the essence 10 thereof as defined in the following claims.

I claim:

1. A knitted stocking provided with a longitudinally extending mock seam comprising a cord attached to the stocking web 15 between floating yarns and opposed loops.
2. A knitted stocking, including wales having draw stitches, and a mock seam cord disposed between the floating yarns on the inner side of the fabric and the opposed 20 draw stitch loops on the face thereof.

3. A knitted stocking provided with a mock seam, consisting of a cord disposed between floating yarns on the inner side of the fabric and draw stitch loops providing eyelets or apertures through which the 25 cord is exposed to view from the face of the fabric.

4. A knitted stocking the fabric of which has longitudinally aligned eyelets or apertures on its face and floating yarns on its 30 inner side, and a cord inserted between the open work face of the fabric and the floating yarns to provide a mock seam.

5. A knitted stocking provided with a mock seam, consisting of a cord disposed between yarns on the inner side of the fabric and open work loops on the face of the 35 fabric across which said yarns are floated.

WILLIAM S. PARKER.
